UNITED STATES PATENT OFFICE.

ABRAM HERZBERG, OF PHILADELPHIA, PENNSYLVANIA.

IMPROVEMENT IN UMBRELLA-FRAMES.

Specification forming part of Letters Patent No. 132,363, dated October 22, 1872.

To all whom it may concern:

Be it known that I, ABRAM HERZBERG, of Philadelphia, Pennsylvania, have invented an Improvement in Umbrella-Frames, of which the following is a specification:

The object of my invention is the simple and economical connection of the ribs of umbrellas to the notches or crown-pieces and the stretchers to the runners; and this object I attain by forming on the notch or runner as many radial projections *a* (shown in the plan view Fig. 1) as the umbrella has ribs, and bending these projections downward and partly around the spherical ends *b* of the ribs, as shown in the vertical section Fig. 2, so that each spherical end is confined to its place partly by two adjoining projections and partly by the stick *A* of the umbrella. Spherical-ended ribs and stretchers have heretofore been attached to notches and runners of umbrellas and parasols,

but in all cases the said ends have been confined between two pieces, the preparation of which and their connection together involved considerable expense, which I obviate by using but one piece having radial projections, and simply bending down the latter so as to confine the spherical ends of the ribs or stretchers, which move as freely as if they were connected by ordinary joints.

I claim as my invention—

The combination of an umbrella-notch or runner, having projections *a*, with the enlarged ends of ribs or stretchers.

In testimony whereof I have signed my name to this specification in the presence of two subscribing witnesses.

ABRAM HERZBERG.
